UNITED STATES PATENT OFFICE

ABRAHAM B. SCHACHAT, OF NEW YORK, N. Y., ASSIGNOR TO NOEL STATHAM, OF IRVINGTON-ON-HUDSON, NEW YORK

FLEXIBLE-FASTENING DEVICE

Application filed March 10, 1926. Serial No. 93,551.

My present invention relates to fasteners, more particularly male and female fastener elements adapted to cooperate in pairs, and flexible fastening members and flexible fastening devices embodying such male and female fastener elements, and aims to devise articles of the general character specified above which are simple in construction, easy, convenient and economical to fabricate and to assemble, which are convenient in operation, which are unusually flexible, which are neat and attractive in appearance, which permit of certain manipulations which increase the range of applicability and the adaptability of the devices of the present invention, and which possess other advantages and superiorities in construction, operation and use in part pointed out in detail hereinafter and in part obvious to those skilled in the art to which the present invention relates. Other objects of the present invention will likewise be in part pointed out in detail herein-after and will in part be obvious to those skilled in the art to which the present invention relates.

In the accompanying specification I shall describe, and in the annexed drawing show, several illustrative embodiments of the articles of the present invention. It is, however, to be clearly understood that my invention is not limited to the specific embodiments thereof herein shown and described but are for purposes of illustration only.

Referring to the drawing, wherein I have illustrated the aforesaid illustrative embodiments of the present invention:

Fig. 1 is a plan view and Fig. 2 a longitudinal section of one form of female fastener element forming a part of one of the aforesaid illustrative embodiments of the present invention;

Fig. 3 is a plan view and Fig. 4 is a side elevation of one form of male fastener element adapted to cooperate with the form of female fastener element shown in Figs. 1 and 2 of the drawing;

Fig. 1^a is a plan view and Fig. 2^a a longitudinal sectional view of another form of female fastener element forming part of another

illustrative embodiment of the present invention;

Fig. 3^a is a plan view and Fig. 4^a a longitudinal sectional view of another form of male fastener element adapted to cooperate with the female fastener element shown in Figs. 1^a and 2^a of the drawing;

Fig. 3^b is a plan view and Fig. 4^b a longitudinal section of still another form of male fastener element constituting a part of a third illustrative embodiment of the present invention;

Fig. 5 is a plan view of the assembled fastener-supporting elements, the male and female fasteners carried thereby, and the key for operating the same;

Fig. 6 is a cross sectional view of the same taken on line 6—6 of Fig. 5 of the drawing;

Fig. 7 is a cross sectional view of the same taken along line 7—7 of Fig. 5 of the drawing;

Fig. 8 is a cross sectional view of the same taken on line 8—8 of Fig. 5 of the drawing;

Fig. 9 is a plan view of another form of female fastener element; and

Fig. 10 a similar view of a cooperating male fastener element which do not involve the angular adjustability feature of the forms of fastener illustrated.

Referring now to the aforesaid illustrative embodiments of the present invention, and more particularly to the drawing illustrating the same, especially the form of the invention illustrated in Figs. 1, 2, 3, and 4 of the drawing, 10 indicates a female fastener element in the form of an elongated member provided with the perforation 11 adjacent one end thereof. The perforation 11 is preferably substantially circular so that the opening provided by such perforation is substantially cylindrical.

20 indicates one of the male fastener elements in the form of an elongated member or slug provided with the knob or protruding portion 21 which is preferably substantially circular, as by being substantially hemispherical. It will thus be noted that by applying the member 10 to the member 20 so that the substantially circular opening 11 passes over the substantially hemispherical knob 21, it is

55

60

100

possible to angularly displace the members 10 and 20 while still maintaining the portion 21 within the perforation 11. This angular displacement may take place either in a single plane, defined substantially as the plane of the meeting faces of the members 10 and 20, or may be out of such plane for a limited range. It will be noted that the lower face 22' of the male fastener element 20 is substantially flat. In any event, such lower face has no means thereon for engagement with another female fastener element of the series of female fastener elements shortly to be described.

15 In Figs. 1^a and 2^a of the drawing is shown a female fastener element 10' likewise in the form of an elongated member provided with a depression 11' rather than a perforation therethrough. In such a case the male fastener element illustrated in Figs. 3^a and 4^a of the drawing may be in the form of an elongated member 20' provided with the knob or protruding portion 21', the lower face 22' of the male fastener element 20', if not absolutely flat, at least has no extension thereon for engagement with another female fastener element, there usually being a slight depression 23' in such lower face 22' corresponding to the raised portion 21' and resulting generally from the method of manufacture of the male fastener element 20' by stamping or the like.

Here also I prefer that the depression 11' shall be semi-circular and that the knob 21' shall likewise be semi-circular in cross section or substantially hemispherical, for co-operation with the substantially semi-circular depression 11' of the corresponding male fastener member 20'. This is for the purpose of permitting a certain degree of angular adjustability with respect to the two series of cooperating male and female fasteners in a manner which will be more fully described later in this specification.

45 Referring now to Figs. 5, 6, 7 and 8 of the drawing, I have shown there a plurality of flexible fastener-supporting elements, generally designated by reference characters 30 and 31, and each preferably comprising the tape portions 30' and 31' and the beaded edge portions 30'' and 31'' which may be made in any desired manner, as by sewing a cord into a folded edge portion of the respective tapes 30' and 31'.

55 The flexible fastener-supporting member 30 preferably carries a series of female fastener elements, such as the female fastener elements illustrated in Figs. 1 and 2 of the drawing, while the flexible fastener-supporting element 31 preferably carries a series of male fastener elements, such as the male fastener elements shown in Figs. 3 and 4 of the drawing or in Figs. 3^a and 4^a of the drawing. It will be noted, in view of the construction 65 of the female and male fastener elements

preferably employed in the device illustrated in Figs. 5, 6, 7 and 8 of the drawing, that while each pair of male and female fastener elements is mechanically interlocked in the closed position of such fastener elements, neither member of each cooperating pair is mechanically interlocked with another fastener element of any other pair of the series of cooperating pairs of male and female fastener elements. This is a novel and unique feature of great importance as rendering the device much more flexible than it otherwise would be and as increasing the ease of operation of the device into and out of open and closed positions.

70 One of the flexible fastener-supporting elements, such as the flexible fastener-supporting element 31, carries a stop member preferably in the form of a clip or rivet 40 for limiting the outward movement of the key 50 shortly to be described in considerable detail herein, while a clip or rivet 41 is provided for uniting the fastener-supporting elements 30 and 31 and for acting as a stop to limit the inward movement of the key 50.

75 The key or operating member 50 may be of any suitable type or construction providing a plurality of converging channels which serve to guide the cooperating pairs of male and female fastener elements into and out of open and closed positions. For example, the key 50 may comprise a plurality of cooperating channel-defining plates 51 and 52 defining between them the channels 53 and 54 which are spaced apart by the wedge-shaped member 55 which separates the plates 51 and 52 and which plates may be soldered or otherwise suitably attached, as to the wedge-shaped member 55. By means of an eyelet 56 or any suitable means, a manipulating 80 handle 57 may be attached to the key 50 so as to permit its manipulation up and down along the flexible fastening device here generally designated by reference character 57.

85 It may here be stated that the outer ends of the male and female fasteners are key-slotted so as to fit tightly over the beaded edges of the respective flexible fastener-supporting members, as indicated by reference characters 15 and 25, respectively. It may here 90 also be stated that the flange portions 51' and 51'', and 52' and 52'', defining the channels 53 and 54, respectively, act on the slotted ends 15 and 25 of the respective male and female fasteners of each pair of cooperating fasteners to guide the same into and out of closing and opening positions, as will be readily apparent to those skilled in the art to which the present invention relates.

95 This completes the description of the construction of the aforesaid illustrative embodiments of the present invention and the manner of assembling the same into a flexible fastening device. The method of operating the illustrative embodiment of the in- 100

vention illustrated in Figs. 5, 6, 7 and 8 of the drawing will likewise be clear to those skilled in the art to which the present invention relates but may be briefly summarized as follows:

- 5 Assuming the device to be partially closed and partially open, as shown in Fig. 5 of the drawing, a movement of the key or operating member 50 by the suitable manipulation of the handle 57, downwardly in the position shown in Fig. 5 of the drawing, causes the wedge-shaped member 55 to be interposed between the cooperating male and female fasteners of each pair, thus opening the device. In the reverse direction of movement 10 of the key or operating member 50, upwardly in the position shown in Fig. 5 of the drawing, the pressure of the flange portions 51' and 51'', and 52' and 52'', on the outer key-slotted ends 15 and 25 of the respective male and female fastener members causes the same 15 to be brought into closed position. The clip or rivet 40 limits the movement of the key 50 upwardly during the closing operation, 20 while the clip or rivet 41 limits the movement of the key 50 downwardly during the opening operation.

The advantages of the foregoing construction are numerous and of great practical importance. The devices are very simple in construction, may be readily and economically fabricated, and may be as readily and economically assembled. The devices are characterized by their ruggedness, their liability to get out of order and their long life. 30 The assembled flexible fastening devices are further characterized by their considerable flexibility and their ease of operation into and out of closed position. Further advantages 35 and superiorities of the devices of the present invention will readily occur to those skilled in the art to which the present invention relates.

It may here be stated that the slotted ends 40 of the male and female fastener elements are sufficiently widely spread to enable them to be clamped down in the desired positions upon the beaded edges of the flexible fastener-supporting elements, as will be readily apparent to those skilled in the art to which the present invention relates. It may here further be stated that in the form of the female fastener elements illustrated in Figs. 1, 2 and 5 to 8, inclusive, of the drawing, 50 in which such female fastener elements are provided with perforations therethrough, the fastening devices embodying such female fastener elements are self-cleaning, that is, the entrance of the protruding portion on each cooperating male fastener elements into the opening in the corresponding female fastener element serves to clean such opening. This adapts the devices of the present invention with particular success in connection 55 with bathing bags and other devices sub-

jected to exposure to dirt, sand and the like.

Since in certain types of construction it may be desirable to have cooperating pairs of fasteners which are not angularly adjustable but which are rather in fixed relation with

respect to each other when in locked position, I may for this purpose use the construction shown in Figs. 9 and 10 of the drawing in which the female fastener elements designated by reference character 60 may each be pro-

vided with a perforation or depression 61, one face of which or one portion of which may be flat or may be provided with other means which by cooperation with the similarly

formed knob or raised portion 62 of the corresponding male fastener element 63 will be designed to prevent such fasteners from having an angular adjustment with respect to each other when in locked position. The flattened portion of the perforation or de-

pression 61 in the female fastener element 60 has been designated by the reference character 61', while the corresponding flattened portion of the knob or extension 63 of the male fastener element 62 has been designated by reference

character 63'. Otherwise, the construction of the fasteners shown in Figs. 9 and 10 of the drawing and the method of applying the same to their respective supporting members are the same as for the fasteners described

previously in this specification. It is, of course, to be clearly understood that other mechanical expedients besides the flattened sides of the perforation or depression and of the corresponding extension on the male

fastener element may be employed where it is desired to prevent the cooperating pairs of fasteners from being angularly adjustable with respect to each other when in locked position.

In Figs. 3^b and 4^b of the drawing, I have shown a male fastener element designated by reference character 20'' and comprising an elongated member or slug provided with a plurality of knobs or protruding portions

21'', 21'', one on each side of the member 20'' and each being preferably substantially circular, as by being substantially hemispherical. It will thus be noted that by applying any of the female fastener elements previously

described to the male fastener element 20'' so that the substantially circular opening of such female fastener element passes over the substantially hemispherical knob 21'', it is

possible to angularly displace the male and female fastener element, while still maintaining the portion 21'' within the perforation or depression in the female fastener element. This action furthermore takes place on each side of the male fastener element 20'' by reason of

the provision of a pair of knobs or protruding portions 21'', 21'', as already described

above.

What I claim as my invention is:

1. A male fastener element comprising an

elongated element provided on one side with a raised portion formed inwardly from one end and the sides thereof, the other side thereof presenting an unbroken and substantially flat surface.

5 2. A male fastener element comprising an elongated element provided on one side with a raised, circular portion formed inwardly from one end and the sides thereof, the other side thereof presenting an unbroken and substantially flat surface.

10 3. A male fastener element comprising an elongated element, provided on one side with a raised, hemispherical portion formed inwardly from one end and the sides thereof, the other side thereof presenting an unbroken and substantially flat surface.

15 4. A flexible fastening member comprising a flexible fastener-supporting element and a series of male fastener elements carried thereby and each comprising an elongated element provided on one side with a raised, hemispherical portion formed inwardly from one end and the sides thereof, the other side thereof 20 presenting an unbroken and substantially flat surface.

25 5. A flexible fastening member comprising a flexible fastener-supporting element and a series of male fastener elements carried thereby and each comprising an elongated element provided on one side with a raised, circular portion formed inwardly from one end and the sides thereof, the other side thereof presenting an unbroken and substantially flat 30 surface.

35 6. A flexible fastening member comprising a flexible fastener-supporting element and a series of male fastener elements carried thereby and each comprising an elongated element provided on one side with a raised portion formed inwardly from one end and the sides thereof, the other side thereof presenting an unbroken and substantially flat surface.

40 7. A flexible fastening device comprising, in combination, a flexible fastening member comprising a flexible fastener-supporting element and a series of female fastener elements carried thereby and each comprising an elongated member provided with a perforation 45 formed inwardly from one end and the sides thereof, and a flexible fastening member comprising a flexible fastener-supporting element and a series of male fastener elements carried thereby and each comprising an elongated 50 element provided on one side with a raised portion formed inwardly from one end and the sides thereof, the other side thereof presenting an unbroken and substantially flat surface.

55 8. A flexible fastening device comprising, in combination, a flexible fastening member comprising a flexible fastener-supporting element and a series of female fastener elements carried thereby and each comprising an elongated member provided with a circular 60

perforation formed inwardly from one end and the sides thereof, and a flexible fastening member comprising a flexible fastener-supporting element and a series of male fastener elements carried thereby and each comprising an elongated element provided on one side with a raised, circular portion formed inwardly from one end and the sides thereof, the other side thereof presenting an unbroken and substantially flat surface.

65 9. A flexible fastening device comprising, in combination, a flexible fastening member comprising a flexible fastener-supporting element and a series of female fastener elements carried thereby and each comprising an elongated member provided with a circular perforation formed inwardly from one end and the sides thereof, and a flexible fastening member comprising a flexible fastener-supporting element and a series of male fastener elements carried thereby and each comprising an elongated element provided on one side with a raised, hemispherical portion formed inwardly from one end and the sides thereof, the other side thereof presenting an unbroken and substantially flat surface.

70 10. A flexible fastening device comprising, in combination, a flexible fastening member comprising a flexible fastener-supporting element and a series of female fastener elements carried thereby and each comprising an elongated member provided with a circular perforation formed inwardly from one end and the sides thereof, and a flexible fastening member comprising a flexible fastener-supporting element and a series of male fastener elements carried thereby and each comprising an elongated element provided on one side with a raised, hemispherical portion formed inwardly from one end and the sides thereof, the other side thereof presenting an unbroken and substantially flat surface, in combination with a slideable key for such flexible fastening device adapted in one direction of its movement along said device to open the same and in the other direction of its movement along said device to close the same.

75 11. A flexible fastening device comprising, in combination, a flexible fastening member comprising a flexible fastener-supporting element and a series of female fastener elements carried thereby and each comprising an elongated member provided with a substantially circular perforation formed inwardly from one end and the sides thereof, and a flexible fastening member comprising a flexible fastener-supporting element and a series of male fastener elements carried thereby and each comprising an elongated element provided on one side with a raised, substantially circular portion formed inwardly from one end and the sides thereof, the other side thereof presenting an unbroken and substantially flat surface, in combination with a slideable key for such flexible fastening device adapted in

one direction of its movement along said device to open the same and in the other direction of its movement along said device to close the same.

6 12. A flexible fastening device comprising, in combination, a flexible fastening member comprising a flexible fastener-supporting element and a series of female fastener elements carried thereby and each comprising an elongated member provided with a perforation formed inwardly from one end and the sides thereof, and a flexible fastening member comprising a flexible fastener-supporting element and a series of male fastener elements carried thereby and each comprising an elongated element provided on one side with a raised portion formed inwardly from one end and the sides thereof, the other side thereof presenting an unbroken and substantially flat 20 surface, in combination with a slidable key for such flexible fastening device adapted in one direction of its movement along said device to open the same and in the other direction of its movement along said device to close 25 the same.

13. A flexible fastening member comprising a flexible fastener-supporting element and a series of male fastener elements carried thereby and each comprising an element provided on one side with a raised, hemispherical portion formed inwardly from one end and the sides thereof, the other side thereof presenting an unbroken and substantially flat 30 surface.

35 In testimony whereof, I have signed my name to this specification this 11th day of February, 1926.

ABRAHAM B. SCHACHAT.
